PATTERN REPRODUCING MACHINE

George F. Ryan, Peabody, Mass., assignor to
 United Shoe Machinery Corporation, Flemington, N. J., a corporation of New Jersey

Application November 8, 1940, Serial No. 364,822

9 Claims.

(Cl. 33—23)

This invention relates to pattern reproduction and is disclosed herein as embodied in a pattern grading machine, for cutting shoe upper patterns, of the type shown in United States Letters Patent No. 2,148,506, granted February 28, 1939, on an application of G. F. Ryan.

A pattern grading machine of this type contains four primary instrumentalities, two of which are movable and are connected by grading mechanisms which are arranged pantographically to modify the length and width of a model independently. That is, all lines drawn in the model parallel to its length are multiplied by a constant and all lines drawn in it parallel to its width are multiplied by an independent constant and are so reproduced in the pattern. A shoe quarter cut from a pattern so graded will not properly fit a last because of excessive height of the heel end of the quarter. This difficulty results from two arbitrary variations from normal grading, one of which occurs in the grading of lasts, and the other in grading of patterns to meet requirements in fitting shoes to the foot.

Because the toe spring and heel height of a last are exaggerated if the last is graded in the ordinary manner, it is necessary to vary the angular relation between the fore and heel parts of the last in accordance with the change in grade to maintain the toe spring and heel height constant. It is apparent that such correction in the grading of lasts by which the heel part is lowered is one cause of the above mentioned excessive height of a pantographically graded shoe quarter at its heel end if the forward portion of the quarter is properly fitted to the last. From the shoe-fitting standpoint, moreover, a shoe quarter must be graded at its rear portion to a substantially lesser extent than at a point in the vicinity of the instep, for example, in order to lower the top line of the quarter sufficiently to avoid its cutting into the ankle of the wearer of the shoe. These matters are different aspects of the same problem as it applies to pattern grading, and this problem has been treated in United States Letters Patent No. 1,807,195, granted May 26, 1931, upon an application of E. H. Burke, and United States Letters Patent No. 1,982,764 granted December 4, 1934, on an application of G. F. Ryan.

The "cutting down" of the pattern along the desired line is effected in the Burke machine by imparting a nonpantographic movement to the model, the tool and model follower in this machine also being movable; and in the Ryan machine a similar effect is produced by imparting a

nonpantographic variation to the normal grading movement of the tool in response to the differential movement between the tool and the model follower in a direction transverse to the grading movement.

In view of the foregoing, the object of the present invention is to provide a simple, accurate and easily operated grading machine adapted for operating upon metal, the normal pantographic grading action of which can be varied to obtain the above mentioned "cutting down" effect in a pattern through any desired portion of the grading operation and without causing any discontinuity in the pattern where the grading action is changed from one type to the other.

As in a machine of the Ryan patent, No. 2,148,506, the illustrated machine comprises four primary instrumentalities, namely, a work holder, a model holder, a model follower, and a tool, and 10 grading mechanism connecting two of them constructed and arranged to utilize the actual movement of one in a certain direction to impart a grading movement to the other in the same direction. The illustrated machine, in accordance 15 with a feature of the invention, includes in its grading mechanism means driven only by the actual movement of the first mentioned instrumentality of the two referred to above in a direction transverse to that of the grading movement. This means, as disclosed herein, comprises a lever 20 mounted and arranged to move bodily in the direction of the grading movement and to swing in response to the movement of the said first mentioned instrumentality in a direction transverse to the grading movement, the swinging movement of the lever being utilized to impart a nonpantographic component to the normal grading movement which is derived from the bodily movement of the lever.

In accordance with another feature of the invention, the lever and mechanism associated therewith is arranged so that its action can be varied as to extent and can be started and stopped at any selected point in the grading operation without causing any discontinuity in the cut made in the pattern.

These and other features of the invention comprising certain combinations and arrangements of parts will be apparent from the following description of an embodiment of the invention shown in the drawings, in which

Fig. 1 is a plan view of a part of an illustrative machine embodying the invention;

Fig. 2 is a view in front elevation of a part of the machine shown in Fig. 1;

Fig. 3 is a sectional elevation, the section being taken along the line III—III in Fig. 2;

Fig. 4 is a sectional plan view of a part of the mechanism shown in Fig. 2, the section being taken along the line IV—IV; and

Fig. 5 is a diagrammatical view illustrating a comparison between the results produced in grading a shoe quarter by the use of the illustrated machine, and by prior practice.

The illustrated machine comprises a frame 10, Fig. 1, upon which are mounted for movement independently of each other in mutually perpendicular directions a work support 12 and a tool head 14, the latter having a rapidly reciprocating tool holder 16 adapted to carry a punch which cooperates with a die to cut a pattern from a piece of sheet material held by the work holder 12.

The work holder 12 is mounted on a carriage 18 which is arranged to move in an east and west direction (lengthwise of the machine) on ways 20 carried by a second carriage 22. The carriage 22 is arranged to move in a north and south direction (crosswise of the machine) on ways 24 mounted on the frame 10. Only one of each of the ways 20 and 24 is included in the part of the machine shown in Fig. 1.

The tool head 14 is mounted on a carriage 26 arranged to move north and south on ways 28 (only one being shown) carried by another carriage 30; and the carriage 30 is mounted to move east and west on ways 32 (only one being shown) which are fixed to the frame 10.

A model 34, from which a pattern is to be reproduced in a work piece held by the support 12, is fixed to a holder 36 mounted on the frame 10. The model 34 is traced by a model follower 38 which is carried by a bracket 40 fixed to the carriage 18. The work piece is thus moved in a path corresponding to the edge of the model and if the tool head 14 is stationary throughout this movement of the work piece the model will be duplicated in the work piece since the punch and the model follower 38 have the same diameter. If it is desired to make an enlarged or reduced reproduction of the model, a grading movement is imparted to the tool head 14 in the north and south direction or the east and west direction, or in both of these directions simultaneously, by separate width and length grading mechanisms which utilize the north and south movement of the work holder 12 and its east and west movement to impart width and length grading movements respectively to the tool head. Of these mechanisms, only the width grading mechanism is illustrated in Fig. 1.

This mechanism comprises a principal grading lever 42 which is pivoted to a bracket 44 fixed to the carriage 30. The lever 42 also comprises an extension 46 which is pivoted at 48 to the lever and is held in any desired angular relation to the lever by a clamp 50. In order to permit the angular relation between the lever 42 and its extension 46 to be varied by definite amounts or to permit one such relation to be definitely and repeatedly established they are connected by an arc 52 fixed to the extension 46 and an arm 54 carried by the lever 42. The arc is provided with a series of holes any one of which is adapted to receive a sliding pin carried by the arm 54. This mechanism is commonly known as a "shift" which will be referred to later. The lever 42 is connected to the tool head 14 by a link 56, one

end of which is adjustable along the lever 42 so as to make it possible to control the extent of the north and south grading movement of the tool head.

As thus far described, the illustrated machine is the same as that disclosed in Patent No. 2,148-506, granted on February 28, 1939, in the name of G. F. Ryan, to which reference may be made for a complete description of the construction and arrangement of the parts of the machine referred to above. It is to be understood that the illustrated machine comprises all of the mechanism of the above mentioned patented machine including a length grading mechanism which is substantially a duplicate of the width grading mechanism referred to above. The length grading mechanism is connected to the tool head 14 by a bar 60 which is pivoted at 62 to the bracket 44, and is driven by the east and west movement of the carriage 18 along the ways 20.

Novel mechanism provided by the present invention is interposed between the extension 46 of the lever 42 and the carriages 18 and 22, the construction and purpose of which mechanism will now be described with reference to a difficulty in pattern grading which this mechanism overcomes.

Referring now to Fig. 5, in which M represents a 4-B model of a shoe part which is to be graded up to a 10-B pattern P, the proper fitting of a series of such shoe parts of different sizes to the corresponding lasts or to the foot requires that the width of the shoe parts along the line D—D be increased in a certain ratio as they are graded up from the model. If the rear portion of the quarter were width graded as along the line C' at the same ratio the top line of the upper would be so high in the larger sizes of shoes as to cut into the ankle of the wearer. It is, therefore, common practice to grade quarters at their rear ends in increments of $\frac{1}{2}$ of an inch between sizes, although the corresponding increment at the position D—D is considerably greater. This result is effected in the use of the machine of the Ryan patent by using the above mentioned "shift," in the following manner.

The model follower 38 is first moved so as to trace the throat of the model M. Fig. 5, the machine having been set so as to "center grade" (1:1 reproduction) whereby the shape of the throat of the model is duplicated in the pattern. Appropriate settings of the length and width grading mechanisms are now made for producing a 10-B pattern P. The rear end of the model is next traced from the throat line to the corner E. At this time the position of the tool relatively to the pattern is at E', the heightwise distance between the points E and E' constituting an excessive increase in the height of the quarter at its rear end as pointed out above. In order to cut down the height of the quarter, the above mentioned "shift" is thrown through as many holes on the arc 52 as may be necessary to move the tool head toward the longitudinal axis of the pattern by the amount which is to be removed from the pattern. This operation of the "shift" causes the cutter to be moved from the point E' to the point F'. The outside edge of the model is now traced by the follower 38 forwardly from the point E for a short distance during which the cutter moves to the point G' on the pattern. The follower 38 is then moved away from the model causing the tool to be moved to the point H'. The "shift" is now thrown back to its original neutral position and the outer edge

of the model is traced by the follower 38, thereby causing the tool to cut the pattern along the line C'. This operation results in an undesirable jog being formed (by the cut E', F', G', and H') below the edge C' of the pattern which must be removed by a hand operation, that is, the pattern after being removed from the machine is sheared and filed along a line J' continuous with the bottom F', G' of the jog and becoming tangent to the edge C' of the pattern rearwardly of the line D, the line J' being made as similar as possible to the corresponding shape of the model according to the judgment of the operator.

This hand operation is subject to the objections of being inaccurate and expensive, the latter objection being aggravated when the patterns are made of metal. It is apparent from Fig. 5 that the cut F', G' cannot be extended very far forwardly of the pattern since this line will always be parallel to the edge C' of the pattern as normally graded and hence will run too deeply into the pattern at its mid-portion where the normal width grade should be maintained. Thus, the "shift" is used merely to measure the height of the rear end of the quarter.

By the use of mechanism now to be described it is possible progressively to vary the width grading movement of the tool head so as to cause the pattern to be cut with a continuous edge requiring no hand finishing, the position of which, at the heel end of the pattern, is the same as it would have been if made by the use of the shift referred to above. This mechanism comprises a bracket 64, Figs. 1 and 2, which is fixed to the carriage 22 and is provided with ways 66 extending in a north and south direction. A carriage 68 is provided with one set of rolls 70 arranged to run on the upper surfaces of the ways 66 and a second set of rolls 72 which are arranged to roll against inclined lateral surfaces on the ways whereby the carriage 68 is permitted to roll freely in the north and south direction only. The carriage 68 is also provided with ways 74 extending in the east and west direction on which ways is mounted for movement in the same direction a carriage 76 having two sets of rolls 78, 80 which engage the ways 74. The carriages 68 and 76 constitute means for driving the extension 46 of the width grading lever 42, the extension 46 being pivoted to a stud 82 fixed to the carriage 76. The above mentioned driving means is moved in a north and south direction to cause a width grading movement of the tool head in response to an east and west movement of the carriage 18 in order to remove, along a continuous line, an unwanted margin from a regular width graded pattern as explained above. This mechanism comprises a second grading lever 84 which is fixed to a shaft 86 rotatably mounted on the bracket 64. An arm 88 is pinned to the shaft 86 so as to rotate therewith and carries a set screw 90 having a conical point adapted to be seated in a recess 92 in a block 94 on the bracket 64 whereby the lever 84 can be located in its central position. The lever 84 is swung in response to an east and west movement of the carriage 18 by connections comprising a gear 96 which is rotatably mounted on the shaft 86 and meshes with another gear 98 fixed on one end of a lever 100. The lever 100 is pivoted at 102 to the bracket 64, and is pivoted at 104 to a carriage 106 arranged to roll freely in only the north and south direction on a runway 108 which is fixed to the end of the carriage 18 adjacent to the tool head 14.

A driving connection between the gear 96 and the arm 88 is effected by tightening a clamp 110 which is threaded on a stud 112 carried by the arm 88 and extending through an arcuate slot 114 in the gear 96. The lever 84 is connected to the carriage 68 by a link 116 which, at one end, is pivoted to the lower side of the carriage at 118. At its other end the link 116 is rotatably mounted on a stud 120 which extends through a wedge shaped block 122 and a T-shaped block 124 arranged to slide lengthwise of the lever 84 along correspondingly shaped grooves therein. The stud 120, and blocks 122, 124 can be locked in any desired position along the lever 84 by a clamp 126, which is threaded on the stud 120. By changing the position of the stud 120 along the lever 84 more or less north and south movement may be imparted to the carriage 68 in response to a given east and west movement of the carriage 18. Definite control of the setting of the stud 120 along the lever 84 is effected by a plunger 128 which is mounted to slide vertically in an arm 130 fixed to the block 122. The plunger 128 is adapted to be received in any of a series of holes formed in an arcuate member 132 fixed to the lever 84. The length of the plunger 128 and its position relative to the clamp 126 are such that when the plunger 128 is fully received in one of the holes of the member 132 the clamp 126 is being swung to lock the stud 120 to the lever 84 is moved directly over the head of the plunger and hence holds the latter in its operative position. When the clamp 126 is released it is moved away from the plunger 128 which then, under the influence of a spring 134, moves upwardly out of engagement with the member 132.

In order to facilitate the resetting of the stud 120 at any desired position at either side of its central position on the lever 84, stops 136 (similar in construction to the blocks 122, 124) are mounted for adjustment on the lever 84 lengthwise thereof and are adapted to be fixed to the lever by means of clamps 138 which are threaded on studs 140 carried by the stops.

The illustrated machine can be used for regular width grading without disturbing the setting of the stud 120, assuming that the latter is not in its central position on the lever 84. To this end, the carriage 68 is locked to the bracket 64 by a set screw 142, Fig. 2, which is threaded in the carriage 68 and is adapted to bear against the outer side of one of the ways 66. Under these circumstances jamming of the machine is prevented by releasing the clamp 110 so as to permit the gear 96 to rotate freely on the shaft 86.

The operation and advantages of the above mentioned mechanism will now be described with reference to the grading of a 10-B pattern P from the 4-B model M of Fig. 5. The throat and back lines of the model are graded as before, the model follower and tool being brought to the points E and E' respectively. With the tool thrown out of operation, the follower 38 is moved to a point K on the edge of the model corresponding to a similarly located point K' on the pattern where the removal of the unwanted margin from the pattern, as regularly graded, is to begin. The position of the follower 38 at K is also such that the carriage 68 is in its central position on the bracket 64 as indicated by an index 144, Figs. 2 and 4, mounted on the carriage 68, and a scale 146 carried by the bracket 64. At this time the lever 84 also will always be in its central position, regardless of the setting of the stud 120, this position of the lever being indicated by the

alignment of a pointer 148 fixed to the bracket 64 with a mark on the end of the lever 84.

The stud 120 is now moved along the lever 84 through as many holes on the member 132 as the "shift" of the prior machine would be thrown to cut down the height of the quarter to the required extent. The follower 38 is now brought to the point E on the model, and the tool is thrown into operation. The edge of the model is next traced by the follower from the point E to the point K during which movement a cut L' is made in the pattern which gradually approaches the edge C' of the pattern as regularly graded and becomes tangent to the latter at a point K', which is the position of the cutter corresponding to the position K of the follower. At this time, the stud 120 is moved back to its central position on the lever 84 preparatory to the regular grading of the portion of the model forwardly of the point K. It is to be understood that Fig. 5 shows a little more than half of a model which is symmetrical with respect to its lengthwise axis. Accordingly, when the follower 38 reaches a point on the complete model opposite to the point K of Fig. 5, the stud 120 will be thrown the same distance as before but on the opposite side of the lever 84. Such setting of the stud 120 causes no discontinuity in the outline of the pattern since the link 116 may be swung freely with respect to the lever 84 while it is in its central position without moving the carriage 68, and hence, without imparting any movement to the tool head 14. It will now be apparent that in response to east and west movement of the follower 38 (and hence, the work holder), between the points E and K, a north and south movement is imparted to the tool head independently of the normal width grading movement which reduces the latter by an amount increasing gradually from zero at the point K' on the pattern to the amount by which the height of the quarter is to be reduced at its heel end. It is also apparent that throughout this cut the tool is under the guidance of the model and that patterns graded from the same model will be similar to each other regardless of their size.

The spacing of the holes and graduations of the member 132 is such that when the stud 120 is set in one of them a certain east and west movement of the work holder (about 4½") will impart the same north and south movement to the cutter head as that provided by throwing the prior "shift" through the same number of holes. If, however, it is desired to provide the same change in the height of the quarter over a smaller or greater distance lengthwise thereof than that referred to above, the following procedure is used: the follower 38 is first placed against the edge of the model at a point corresponding to that on the pattern from which the cutting down of the height of the pattern is to begin. The latch 110 is released and the lever 84 is located in its central position by means of the screw 90. The clamp 118 is now tightened and the screw 90 is released. The follower 38 is next placed at the point E on the model and then the stud 120 is adjusted along the lever 84 until the index 144 on the carriage 68 is opposite to a graduation on the scale 146 corresponding to the same number of holes on the "shift" which would effect the required north and south movement of the tool head. It is thus apparent that by the use of the scale 146 as above described, an operator is enabled to obtain the same cutting off effect at

the rear end of a pattern as was formerly obtained by the use of the "shift."

The follower 38 is now moved forwardly along the edge of the model from the point E until the pointer 148 indicates that the lever 84 has again reached its central position. The tool at this time is located at the edge of the pattern as regularly graded. The machine now is again set for regular grading either by moving the stud 120 to its central position in the lever 84, or by clamping the carriage 68 to the bracket 64 by means of the set screw 142 and releasing the clamp 110. Thus, regardless of where the transition occurs between regular grading and that resulting from the use of the mechanism provided by the invention, the pattern can be cut not only at the correct height at the heel end but also along a line having no discontinuity in it where the grade is changed from one type to the other.

It should be understood that the invention comprehends a machine of the type disclosed herein having a substantial duplicate of the grading apparatus carried by the bracket 64 associated with the ordinary length grading apparatus. That is, such a machine would have attached to the right-hand end of the carriage 18 a bracket similar to the bracket 64 and carrying mechanism similar to that which is mounted on the bracket 64. Such a mechanism would utilize north and south movement of the carriage 18 to vary the usual east and west grading movement of the tool head as in grading a continuous line of the model extending in the north and south direction.

Having thus described my invention, what I claim as new and desire to secure by Letters Patent of the United States is:

1. In a pattern reproducing machine, four primary instrumentalities, namely, a model holder, a work holder, a model follower, and a tool, two of said instrumentalities being movable and connected by grading mechanism constructed and arranged to utilize the actual movement of one of them in a certain direction to impart a grading movement to the other in the same direction, and means driven only by the actual movement of the said one instrumentality in a direction transverse to that of the grading movement for varying the extent of the grading movement effected by said mechanism.

2. In a pattern reproducing machine, four primary instrumentalities, namely, a model holder, a work holder, a model follower, and a tool, two of said instrumentalities being movable and connected by grading mechanism constructed and arranged to utilize the actual movement of one of them in a certain direction to impart a pantographic grading movement to the other in the same direction, and means driven only by the actual movement of the said one instrumentality in a direction transverse to that of the grading movement for adding a nonpantographic component to said grading movement.

3. In a pattern reproducing machine, four primary instrumentalities, namely, a model holder, a work holder, a model follower, and a tool, two of said instrumentalities being movable and connected by grading mechanism constructed and arranged to utilize the movements of one of them in each of two mutually transverse directions to impart a grading movement to the other in one of said directions, said mechanism comprising a lever mounted to move bodily in the direction of the grading movement, and connections between said lever and the said one instrumentality con-

structed and arranged to swing said lever in response to only actual movement of the said one instrumentality transverse to said grading movement whereby the extent of the grading movement effected by the bodily movement of said lever is varied.

4. In a pattern reproducing machine, four primary instrumentalities, namely, a model holder, a work holder, a model follower, and a tool, two of said instrumentalities being movable and connected by grading mechanism constructed and arranged to utilize the movements of one of them in each of two mutually transverse directions to impart a grading movement to the other in one of said directions, said mechanism comprising a lever mounted to move bodily in the direction of the grading movement and to swing in opposite directions from a central position, means for locating said lever in its central position, means operated in response to only the actual movement of the said one instrumentality transverse to the grading movement for swinging said lever, and connections for establishing a driving relation between said lever and last-mentioned means, said connections being operable to permit said lever to swing freely into its central position when said locating means is operated.

5. In a pattern reproducing machine, four primary instrumentalities, namely, a model holder, a work holder, a model follower, and a tool, grading mechanism comprising a principal grading lever associated with one instrumentality and a second grading lever associated with a second instrumentality, said second lever being mounted to move bodily with said second instrumentality in one direction to effect a grading movement of the said one instrumentality and to swing about an axis, means operated by movement of said second instrumentality transverse to said direction for swinging said second lever, and a member connected to said principal lever and mounted on said second lever for adjustment toward and from said axis whereby the extent of the grading movement effected by the bodily movement of said second lever is varied by its swinging movement.

6. In a pattern reproducing machine, four primary instrumentalities, namely, a model holder, a work holder, a model follower, and a tool, two of said instrumentalities being movable and connected by grading mechanism constructed and arranged to utilize the actual movements of one of them in each of two mutually perpendicular directions to impart a grading movement to the other in one direction, said mechanism comprising a lever associated with the said one instrumentality and mounted for translatory movement and also to swing in response to the perpendicular movements respectively, and means connecting said lever and said other instrumentality for utilizing the swinging movement of said lever to increase or diminish the grading movement effected by the translatory movement of said lever.

7. In a pattern reproducing machine, four primary instrumentalities, namely, a model holder, a work holder, a model follower, and a tool, two of said instrumentalities being movable and connected by grading mechanism constructed and arranged to utilize the actual movements of one of them in each of two mutually perpendicular directions to impart a grading

movement to the other in one direction, said mechanism comprising a principal grading lever associated with said other instrumentality, and a second lever associated with the said one instrumentality, the second lever being mounted for translatory movement and also to swing in response to the said perpendicular movements respectively, and means connecting said second lever with said principal lever for utilizing the swinging movement of said second lever to vary the grading movement effected by the translatory movement of said second lever.

8. In a pattern reproducing machine, four primary instrumentalities, a model holder, a work holder, a model follower, and a tool, two of said instrumentalities being movable and connected by grading mechanism constructed and arranged to utilize movement of one of them in each of two mutually perpendicular directions to impart a grading movement to the other in one of said directions, a carriage mounted for movement in the direction of grading movement, a second carriage on which said one instrumentality is mounted, said second carriage being mounted for movement on the first-mentioned carriage in a direction transverse to that of the grading movement, said grading mechanism comprising a principal grading lever and a second grading lever rotatably mounted on one of said carriages, means operated by the actual movement of the other carriage for rotating said second lever, means for driving said principal grading lever mounted on said first-mentioned carriage for movement in the direction of the grading movement, and a link connecting said driving means and said second grading lever, said link being adjustable along said second grading lever whereby the grading movement effected by the said first-mentioned carriage can be varied.

9. In a pattern reproducing machine, four primary instrumentalities, namely, a model holder, a work holder, a model follower, and a tool, two of said instrumentalities being movable and connected by grading mechanism constructed and arranged to utilize the actual movement of one of them in a certain direction to impart a grading movement to the other in the same direction, a carriage which is movable in the direction of the grading movement, the said one instrumentality being mounted for movement on said carriage transverse to the grading movement, said grading mechanism comprising a lever mounted for movement with said carriage, mechanism connecting said lever and said other instrumentality comprising a member mounted for movement with said carriage and also relatively thereto in the direction of the grading movement, means connecting said one instrumentality and said lever for swinging said lever in response to movement of said one instrumentality on said carriage whereby said member is moved relatively to said carriage, means for holding said member immovable relatively to said carriage and means for rendering the first-mentioned means inoperative when said member is fixed to said carriage whereby grading movement is imparted to said other instrumentality in response to movement of said one instrumentality only in the direction of the grading movement.

GEORGE F. RYAN.
